UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

STEAM BOILER

Application filed December 19, 1924. Serial No. 756,867.

My invention will best be understood by reference to the accompanying drawings in which I have illustrated a preferred form thereof and in which Fig. 1 is a sectional view taken through a steam boiler illustrating my invention; Fig. 2 is a fragmentary sectional view illustrating the ends of certain tubes connected to a drum; Fig. 3 is an inverted plan view of Fig. 2 and Fig. 4 is a longitudinal section through an end portion of a tube, made in accordance with my invention.

Like reference characters indicate like parts throughout the drawings.

Referring now to the drawings, and first to Fig. 1, 10, 11 and 12 are upper transverse steam and water drums of a steam boiler of the general Stirling type, the drums 10 and 11 being connected by steam circulating tubes 13 and water circulating tubes 14, while the drums 11 and 12 are connected by steam circulating tubes 15. A lower mud drum 16 is connected to the upper steam and water drums by banks of tubes 17, 18 and 19, respectively, baffles 20, 21 and 22 being provided for directing the gases from the furnace chamber 23 in a plurality of passes over the boiler tubes in a known manner, to an outlet flue 24. The front and rear walls of the setting are indicated by the reference numerals 231 and 232 respectively. I have illustrated the furnace as provided with an ordinary grate 25.

Referring now more particularly to Figs. 2, 3 and 4, it will be seen that each of the tubes 191, the inner as well as the outer diameters, are reduced at their ends, as at 192, it being understood that each of the tubes is also preferably reduced at its opposite end, as illustrated in Fig. 1, by a swaging or other desired operation. The reduced ends of the tubes are expanded into the tube sheet, as at 26, in the usual manner. The ends of the tubes are preferably curved as illustrated in Fig. 1 and have straight end portions reduced in diameter received in the openings of the drum. It is advantageous to make the re-

duced end portions straight as a special tube cleaner may be more readily passed through the reduced portions of the tubes.

By reducing the diameter of the ends of the tubes, which are connected to the tube sheets in the described manner, the openings therein are made correspondingly smaller than they otherwise would be, thereby resulting in an increase in the ligament efficiency of the tube sheet and rendering it possible to use a higher steam pressure in the boiler for the same thickness of boiler plate than would otherwise be possible. For example, with a boiler plate two inches in thickness and with boiler tubes three and one-quarter inches in diameter, the maximum pressure allowed for a Stirling boiler is 420 pounds. By reducing the outer diameter of the tubes from three and one-quarter inches to two and one-half inches, where they enter the tube sheet, the working pressure for a two inch thick plate may be made 560 pounds, and still maintain substantially the same heating surface that the boiler would have if the tubes were of uniform diameter throughout.

The tubes are reduced in external diameter at one end at least, and preferably at both ends, where they enter the drums sufficient in extent lengthwise of the tubes to permit sufficient movement of one of the reduced ends of a given tube through its opening in the associated drum to permit of the insertion of the opposite end of the tube in its opening in the associated drum and its removal therefrom. When a tube is installed, one of the reduced ends is passed through a tube hole in the associated drum a sufficient distance to bring the other end opposite its tube hole in the associated drum thereof, after which the tube is removed a sufficient distance from the tube hole in which it is first inserted to make it come to its proper position in the boiler. It will be understood that in inserting a tube, it is passed through one of the wider lanes provided between each two circumferential

rows of tubes. It will be noted from Figs. 1 and 2 that the tubes are reduced at their ends a distance lengthwise thereof sufficient to permit the tubes to be installed in the foregoing manner. Furthermore, the curved ends of the tubes assist in inserting the tubes, as the tube can be held at an angle to its final position and twisted in inserting it through the first tube hole when it is brought to a position where the opposite end comes opposite the second tube hole, and the installation can be made without subjecting the metal surrounding the first tube hole to substantial strains.

15 I claim:

1. In a high pressure steam boiler, two spaced drums each provided with openings, a bank of water tubes the ends of which are adapted to enter the openings of the respective drums in a plurality of circumferential and longitudinal rows, the portions of the drums entered by said tubes being of substantially uniform thickness, each tube being reduced in external diameter at one end at least where it enters the drum sufficient in extent lengthwise of the tube to permit sufficient movement of the reduced end of the tube through its opening in the associated drum to permit of the insertion of the opposite end of the tube in its opening in the associated drum and its removal therefrom, the intermediate portions of the tubes being relatively large to provide a relatively small gas flow area therebetween.

35 2. A water tube boiler comprising two parallel cylindrical drums each provided with openings, a bank of tubes connecting said drums and having curved ends terminating in reduced end portions at each end which enter the openings in said drums, the tubes being spaced from each other transversely of the bank and from the front to the back of the bank, said tubes being unreduced throughout the major portion of their 40 lengths, and reduced at their ends a distance that will permit the end of a tube to be passed a sufficient distance through the opening in one of the drums to bring the opposite end of the tube opposite the opening in the other 45 drum, after which said other end may be made to enter said other drum and the tube brought to its final position in the boiler and in the correct position to be expanded into 50 said opening.

55 3. A water tube boiler comprising two parallel cylindrical drums each provided with openings, a bank of tubes connecting said drums and having curved ends terminating in reduced straight end portions at each end 60 which enter the openings in said drums in a substantially radial direction, the tubes being spaced from each other transversely of the bank and from the front to the back of the bank, said tubes being unreduced throughout 65 the major portion of their lengths, and re-

duced at their straight ends a distance sufficient to permit the end of a tube to be passed a sufficient distance through the opening in one of the drums to bring the opposite end of the tube opposite the opening in the other 70 drum, after which said other end may be made to enter said other drum and the tube brought to its final position in the boiler and in the correct position to be expanded into said opening.
